UNITED STATES PATENT OFFICE.

JOHN PRESSLEY COLEMAN, OF EDGEWOOD PARK, PENNSYLVANIA,
ASSIGNOR TO THE UNION SWITCH AND SIGNAL COMPANY, OF
SWISSVALE, PENNSYLVANIA.

RELAY.

SPECIFICATION forming part of Letters Patent No. 617,854, dated January 17, 1899.

Application filed January 20, 1898. Serial No. 667,286. (No model.)

To all whom it may concern:

Be it known that I, JOHN PRESSLEY COLEMAN, a citizen of the United States, residing at Edgewood Park, in the county of Allegheny and State of Pennsylvania, have invented or 5 discovered certain new and useful Improvements in Relays, of which improvements the following is a specification.

The invention described herein relates to 10 certain improvements in relays, the improvement being especially applicable to that class or kind of relays known as two or three point relays. It has heretofore been customary to form the contact-finger of the relay of light 15 resilient material riveted or otherwise fixedly attached to the armature or its lever, so that it will yield when its end is brought into contact with one of the stops by the movement of the armature-lever toward the magnets. 20 Considerable difficulty has been encountered in so adjusting the magnets, armature, and contact stops and plates that both of the latter will be brought simultaneously against their stops. Unless these parts are thus accurately adjusted one of the contact springs 25 or plates will strike against its stop and wholly prevent or present considerable resistance to the movement of the other contact plate or plates against the other stop or 30 stops.

The object of the present invention is to so construct the several parts that entire freedom or flexibility of movement of the armature on its lever and the contact-plates on 35 their supports can be attained.

In general terms the invention consists in the construction and combination substantially as hereinafter more fully described and claimed.

40 In the accompanying drawings, forming a part of this specification, Figure 1 is a sectional elevation, the plane of section being indicated by the line I I, Fig. 2. Fig. 2 is a plan view of the under side of the relay, showing the lever-armature and contact-plates. Fig. 3 is a sectional elevation, the 45 plane of section being indicated by the line III III, Fig. 2. Fig. 4 is a sectional plan view, the plane of section being indicated by

the line IV IV, Fig. 3. Fig. 5 is a sectional 50 elevation, the plane of section being indicated by the line V V, Fig. 1; and Fig. 6 is a perspective view of the armature-lever and parts carried thereby.

In the practice of my invention the magnets 1 are secured to the cap-plate 2, which is provided with openings to permit the poles of the magnets to project through by means of bolts 3, passing through the cap-plate and screwing into the end plate 4, to which the 60 upper ends of the magnets are attached. On its under side the cap-plate is provided with depending lugs 5, provided with threaded openings for the reception of the threaded plugs 6, having conical recesses in their ends 65 for the reception of the correspondingly-shaped ends of the shaft or spindle 7. This shaft or spindle serves as a pivotal support for the lever 8, which is secured to said shaft, so that the latter will move therewith. In 70 order that the lever may move freely either toward or from the magnets, a weight 9 is secured thereto on the opposite side of the shaft or spindle of such size as to nearly counterbalance the weight of the parts carried by the lever, as hereinafter described. The armature 10 is secured upon the transverse pin 11, whose projecting ends are made conical to fit in corresponding seats formed, 75 respectively, in a shoulder on the lever and the end of a pin 12, screwing through a lug 13, formed on or secured to the lever, as clearly shown in Figs. 1, 4, and 6. This pin 11 is secured to the armature about midway 80 of the length of the latter, and the lever is so secured on the shaft or spindle 7 that it will lie in a plane passing between the magnets 1, as clearly shown in Figs. 2 and 5. It will be observed that the axes of rotation of the 85 shaft 7 and pin 11 are in planes at right angles to each other, and so form a universally-jointed support for the armature.

One or more contact-plates 15, preferably slightly resilient, are attached to the armature. These plates are carried by arms 14, 95 which are secured to, but insulated from, the armature 10 on either side of its pivotal support, and to the projecting ends of these arms.

are pivotally connected the contact-plates 15, preferably by means of blocks 16, which are riveted or soldered to the contact-plates and pivotally connected to the arms. These blocks 16 are so attached to the contact-plates and so pivotally connected to the arms that the plates are weighted by said blocks so as to hold lugs or stops 17 against the arms and thereby maintain the plates in a horizontal position, but with a freedom of movement under circumstances to be hereinafter described. While the ends of the contact-plates may be so shaped as to form bearings to strike against the bearing-plates in the ends of stops 18, it is preferred to employ platinum as the bearings on the plates 15 and the stops 18. These stops 18, which form the front contacts, consist of a bolt passing through, but insulated from, the cap-plate 2 and having their stem portions threaded for the reception of a holding-nut 19 and a clamping-nut 20, whereby the wire conductor can be electrically connected therewith. The back contacts are formed by screws 21 passing through bars 22, having one end supported by, but insulated from, arms 23, which project laterally from a bracket 24, secured to the under side of the cap-plate 2. The opposite ends of these bars 22 are electrically secured to the lower ends of elongated heads 25, which are provided with threaded stems 26, passing through, but insulated from, the cap-plate 2 and are held in place by nuts 27. On these stems are also screwed clamping-nuts 28, whereby the ends of conductors can be secured. It will be observed that this construction forms very effective electrical connection between back-stops 21 and the conductors.

Under the usual and normal operation of this device the back-stop 21 will be sufficient for the operation of the relay; but as it sometimes occurs that the contact-plates become welded or attached to the front contacts by reason of heavy currents passing along the conductors provision is made for the formation of a shunt-circuit around the relay. This shunt-circuit is, as described in application Serial No. 660,473, filed December 2, 1897, formed in part by the contact-plates 15 and auxiliary back contact-points 21^a. These auxiliary back contacts are formed by screws passing through the bars 22 in such position that when the forward ends of the contact-plates adhere to the front contact-points their rear ends will strike against the back contacts 21^a when the magnets are deenergized, all as fully described in the application referred to.

It is characteristic of my improvement that the axes of the pivotal supports of the lever 60 and armature are arranged at or approximately at right angles to each other and that said axes are in the same or parallel planes, which are at or approximately at right angles to a plane passing through the axes of the cores of the magnets. By reason of such construction and arrangement of the pivotal supports the armature can readily accommo-

date itself and be brought into contact with the poles of the magnets, in case the latter should lie in different horizontal planes, the pivotal support of the armature on its lever permitting the automatic adjustment of the armature to the positions of the poles of the magnet. Also the pivotal connection of the contact-plates to the pivotally-mounted armature will permit of the automatic adjustment of the contact-plates in case the front contact-points should be in different horizontal planes, thereby insuring good electrical contacts even when parts of the relays should be somewhat out of normal position.

As described, in the application above referred to, the movable parts of the relay are inclosed in a glass shell 29, which is clamped between the cap-plate 2 and the bottom plate 30, thereby hermetically sealing such movable parts and permitting the easy inspection thereof.

I claim herein as my invention—

1. The combination of a magnet, a lever pivoted in suitable relation to the poles of the magnet, and an armature pivotally mounted on the lever with its pivotal axis at right angles to the axis of the lever, the axes of the pivotal supports of the lever and armature being in the same or parallel planes, which are at or approximately at right angles to a plane passing through the axis of the magnet, substantially as set forth.

2. The combination of a magnet, an armature and pivotal supports for the armature having their axes at right angles to each other and lying in the same or parallel planes which are at right angles to a plane passing through the axis of the magnet, substantially as set forth.

3. The combination of a magnet, an armature, pivotal supports for the armature so arranged as to permit of movements of the armature in planes at an angle to each other and contact-plates pivotally mounted on the armature, substantially as set forth.

4. The combination of a magnet, an armature, pivotal supports for the armature having their axes at or approximately at right angles to each other, and lying in the same or parallel planes, which are at or approximately at right angles to a plane passing through the axis of the magnet and contact-plates attached to the armature, substantially as set forth.

5. In a relay the combination of a magnet, an armature, contact-plates pivotally mounted on the armature, a binding-screw, a bar secured to the binding-screw, and a screw passing through the bar and forming a back contact for the contact-plates, substantially as set forth.

In testimony whereof I have hereunto set my hand.

JOHN PRESSLEY COLEMAN.
